UNITED STATES PATENT OFFICE.

CHARLES METREWITZ, OF CHICAGO, ILLINOIS.

DRAIN BOARD FOR WRINGERS.

Application filed April 7, 1927. Serial No. 181,629.

This invention relates to a drain board for clothes wringers and the like and is a continuation in part of my co-pending application for "wringer", Serial No. 112,432, filed 5 May 29, 1926.

The invention relates more particularly to a combined clothes feeding platform and drain board which may be removably attached to either side of a wringer.

10 It is an object of this invention to provide a removable unit for wringers and the like comprising a feeding platform and a drain board.

15 A further object of this invention is to provide a removable drain board having means removably associated therewith to prevent the catching or tearing of clothes thereon and to act as a retaining splash board for the water flowing down the drain board.

20 Other and further important objects of this invention will be apparent from the disclosures in the specification and the accompanying drawings.

25 The invention (in a preferred form) is illustrated in the drawings and hereinafter more fully described.

On the drawings:

Figure 1 is a vertical sectional view of a device embodying features of this invention associated with a wringer.

30 Figure 2 is a plan view of the device itself.

Figure 3 is a bottom plan view of the device and wringer as shown in Figure 1.

35 Figure 4 is a fragmentary vertical sectional view taken substantially along line IV-IV of Figure 3.

Figure 5 is a fragmentary rear elevational view of a part of the device.

As shown on the drawings:

30 The usual type of wringer is shown which comprises a base rail 1, vertical side stiles 2, the upper bridge 3, and the rolls 4. The combined drain board and feeding platform structure comprises a thin metal water or drain board 5 having integral upwardly turned sides 6 which are provided at one end with laterally extending arms 7, which arms, of course, may be integral with the sides 6 if so desired. Pivoted at 8 to the arms 7 is a thin metal delivery platform or tray 9 having integral upturned sides 10 thereon. This delivery platform 9 is provided with a curled edge 11 which removably engages over a suitable rod 12 secured to the stiles 2. A second rod 12^a, similar to rod 12, is also provided 55 on the opposite side of the wringer. The

clothes delivery platform 9 is also provided with a supporting arm or bracket 13, pivoted as shown at 14 to a plate 14^a secured to the platform 9, and which extends into a keeper 15 secured to the base rail 1. It will be noted 60 that the supporting bracket 13 is provided with a depending lug 16 a short distance from the free end thereof for engaging the edge of the keeper 15 to maintain the platform 9 in proper position. The keeper 15 is provided 65 with a stop 17 so positioned that when the free end of the supporting bracket 13 abuts thereagainst the bracket will be substantially normal to the keeper. A second stop 17^a is provided in the keeper 15 for abutment by the 70 bracket 13 from the opposite side of the keeper.

The sides 6 of the drain pan 5 at the free end thereof are provided with arms 18 which support a transverse rod 19 therein. Re- 75 movably suspended on this rod 19 is an apron or splash board 20 having a curled edge 21 thereon which loosely engages over the rod 19. Opposite to the curled edge 21 the drain board 20 is provided with a curled edge 22 80 which aids in preventing the clothes from catching on the edge of the drain board when being fed into the rolls 4. The drain board 20 also has integral angular sides 23 outwardly extending therefrom which aid in 85 guiding the clothes when being fed into the wringer. To the opposite side of the apron 20 is secured a plate 24 to which a locking key 25, having a handle 26 thereon, is pivoted as shown at 27. The key is provided adjacent 90 its top end with an angular portion 28 adapted to abut the curled edge 21 of the apron 20 when the key is in a substantially vertical position thereby securing the apron 20 to the rod 19. To release the key the handle 26 is 95 merely rotated to the right or to the left thus releasing the angular portion 28 from engagement with the rod 19, stops 29 being provided to limit the pivotal movement of the key 25.

100 As shown in full line position in Figure 1, the combined drain board and feeding board are in position for use. However, if it is desired to utilize the structure from the opposite side of the wringer, it is only necessary 105 to swing the bracket 13 from its engagement with the keeper 15, disengage the curled end 11 of the delivery platform 9 from the rod 12, and slide the drain board 5 outwardly from underneath the rolls. Then the device 110

may be secured to the wringer on the opposite side thereof as shown by the dotted line 5 position in Figure 1, the curled end 11 of the delivery platform 9 engaging with the rod 12^a and the supporting bracket 13 engaging with the keeper 15 from the opposite side thereof, and abutting stop 17^a. It is to be noted that in either position of the device, the drain board 5 extends back completely 10 under the rolls where it will catch all drippings from the rolls thereby safeguarding any structure on or over which the wringer is mounted. Obviously, the apron 20 if so desired may be easily removed from the drain 15 board 5 by turning the handle 26 to the right or to the left to disengage the key from the rod 19, and then lifting off the apron.

From the foregoing, it is apparent that I have provided a novel unitary structure including both a delivery platform and a drain board which affords a decided advantage over the present structures, inasmuch as it permits both the delivery platform and drain board to be simultaneously removed from a 25 wringer. It will be appreciated that this construction allows a substantially large feeding platform and drain board to be used, since they are pivotally connected to each other and removable together from the 30 clothes wringer or the like.

I am aware that many changes may be made and numerous details of construction may be varied through a wide range without departing from the principles of this invention and I, therefore, do not purpose limiting the patent granted hereon, otherwise than necessitated by the prior art and the spirit and scope of the appended claims.

I claim as my invention:

- 40 1. In combination, a delivery board, a drain board pivotally secured thereto, and a splash board attached to said drain board.
2. A delivery tray, means for removably mounting the same on a wringer, a drain 45 board pivotally secured to said tray, swingable supporting means for said delivery tray, to removably engage a portion of said wring-

er, and an apron removably suspended from said drain board.

3. The combination with a wringer, of a 50 combined clothes delivery platform and water board comprising a pair of members pivotally connected, one member having a curled end adapted for removable engagement with a rod on said wringer, and having a swingable 55 bracket engageable with a keeper on said wringer.

4. In a device of the class described, a delivery tray, a drain board pivotally connected thereto, a splash apron removably suspended 60 from said drain board, and means for securing said splash apron in position.

5. The combination with a wringer having transverse rods on each side thereof and a keeper on the bottom thereof, of a delivery 65 platform adapted to be suspended from one of said rods on one side of the wringer, an arm pivoted to said platform and engageable with said keeper, and a drain board pivotally secured to said platform and extending on 70 the opposite side of the wringer.

6. The combination with a wringer having a supporting rod on each side thereof and a keeper adjacent the bottom thereof, of a delivery tray removably suspended on one side 75 of said wringer from one of said rods, a supporting arm pivoted to said tray and adapted to removably engage with said keeper, a drain board pivotally secured to said delivery tray and extending from the opposite side of said wringer, and a splash apron removably suspended from the outer end of said drain board.

7. A combined delivery platform and drain board comprising a pair of pivotally 85 connected members, means on one of said members for suspending the same from a wringer or the like, and supporting means pivoted to one of said members.

In testimony whereof I have hereunto subscribed my name at Chicago, Cook County, Illinois.

CHARLES METREWITZ.
